Fig. 5

Fig. 1 is a perspective view of an air jig embodying my new design;

Fig. 2 is a top plan view;

Fig. 3 is a rear elevational view;

Fig. 4 is a front elevational view;

Fig. 5 is a side elevational view; and

Fig. 6 is a side elevational view of the air jig, as viewed from the side opposite Fig. 5.

The dominant features of my design reside in the portions shown in full lines.

Portions of the jig are broken away in Figs. 3, 4, and 6 for the convenience of illustration only.

I claim:

The ornamental design for an air jig, substantially as shown and described.
